BOOT JACK

Frank O. McDougle, P.O. Box F,
Fairland, Okla. 74343

Filed May 8, 1974, Ser. No. 467,871

Term of patent 14 years

Int. Cl. D3—99

U.S. Cl. D86—10 D

FIG. 1 is a right side elevational view of a boot jack embodying my novel design;

FIG. 2 is a front elevational view thereof;

FIG. 3 is a left side elevational view thereof;

FIG. 4 is a rear end elevational view thereof;

FIG. 5 is a top plan view thereof; and

FIG. 6 is a bottom plan view thereof.

I claim:

The ornamental design for a boot jack, substantially as shown and described.
